UNITED STATES PATENT OFFICE.

WILLIAM HENRY SCOTT, JR., OF NEW YORK, N. Y., ASSIGNOR TO SUSQUEHANNA SILK MILLS, OF NEW YORK, N. Y., A CORPORATION OF NEW YORK.

PROCESS OF MAKING FABRIC.

1,275,771.

Specification of Letters Patent. Patented Aug. 13, 1918.

Application filed January 21, 1918. Serial No. 213,029.

To all whom it may concern:

Be it known that I, WILLIAM H. SCOTT, Jr., a citizen of the United States of America, residing at 149 Madison Ave., New York city, in the county of New York and State of New York, have invented certain new and useful Improvements in Processes of Making Fabric, of which the following is a specification, reference being had therein 10 to the accompanying drawings.

This invention relates to a new fabric and the process of making same.

The object of my invention is the production of a valuable fabric at a very low 15 cost and at the same time the reproduction of the effect of certain high class fabrics known in the art as "covert-coats" in an inexpensive and rapid way that will involve minimum commercial risks in merchandising such new substitute and through its 20 lower cost make the beauty of the original covert-coats accessible to a much larger field of application.

Another object of my invention is the production of a new fabric, using as a basis 25 of my work a piece-dyed, ribbed fabric and then so treating this piece-dyed fabric by a relatively simple yet novel method for producing a handsome finished cloth or fabric.

With these and other objects in view, my 30 invention consists of certain constructions and arrangements of parts as will herein-after be fully described and claimed.

In the drawings:—

Figure 1 is a diagram of a machine used 35 in my process for producing my new fabric.

Fig. 2 is a plan view of piece-dyed fabric prior to being treated in the manner hereinafter specifically described, while,

Fig. 3 is a plan view of a piece of finished 40 fabric produced in accordance with the present invention.

Fig. 4 is an enlarged fragmentary view 45 of a portion of the engraved roller, my fabric and the primary roller, shown in general outlines in Fig. 1.

Fig. 5 is a fragmentary, enlarged, perspective view of the engraved roller, for 50 indicating the fine lining, or delicate surfaced construction thereof.

In carrying out the present invention, it is to be understood that my process relates particularly to surface printing and that the

process pertains more particularly to the treatment of ribbed goods and especially to 55 piece-dyed silk-warp ribbed goods.

I have found after long experience in the art to which this invention relates that by taking uneven, or more particularly ribbed goods, and placing the same on supply roller 1, Fig. 1, passing the goods 2 around the primary roller 3, causing the engraved roller 4 to impress lightly the cloth 2 on only one face thereof, that a very beautiful effect is produced upon one surface of the fabric, 60 and that this simple process as herein described greatly increases the value of an ordinary piece-dyed fabric of the above character.

The engraved roller 4 (see more particularly Figs. 4 and 5) is very fine lined in its engraving and the depth of engraving is so regulated that the coloring matter will only cause an extremely light coat to be placed upon the fabric which coat really 70 amounts to only a "specking" since the application of minute quantities of color does not permeate the entire cloth. The warp threads in a silk warp ribbed fabric cover to a large extent the filling threads somewhat like a grate and are the ones on which in view of the very shallow engraving used in my process, the color or specking effect is 75 the greatest (see Fig. 4).

For the value of the product of my process 80 it is necessary that this is the case as the original dye color of the fabric will shine through the small openings of the warp threads and blend both colors, the dyed and the superficially applied ones, into 85 a harmonious appearance without showing any design.

I have found that it is quite essential that the engraving carrying the coloring matter is in its units smaller than the distance between two picks (filling threads) that are contained in the fabric, that is to be converted according to my process. The product of my process is essentially the outcome of a careful study of depths of engraving, 95 its unit length in proportion to the distance between two picks, and the thickness and roundness of the ribs in the fabric that is to be treated.

As a result of extensive and practical experience with this fabric, I find that the 100

best results are obtained on silk-warp, ribbed piece-goods, but substantially the same results can be obtained with any ribbed goods.

It is to be understood that in my process, 5 I produce this beautiful fabric with a comparatively few number of picks (filling threads), the reduction of the picks or filling threads in my fabric materially reducing the cost of manufacture. Though, therefore, 10 the construction of the fabric is a coarse one in the filling threads, nevertheless, through the application of minute quantities of color, of which there falls more than one unit onto one rib in the vast majority 15 of the impressions between roller and fabric, the effect created on the single thread in the rib is the one that could in the common art only be produced with a plurality of threads of different color which 20 would obviously and materially increase the cost of manufacture.

It is to be understood that the treatment of the fabric shown in Fig. 2 to a light coating of coloring matter amounting to "specking" 25 of one surface of the goods, produces what appears to be a changeable color effect only on one side and that the character of its gloss is infinitely more refined than the character of changeableness that is commonly produced in the market through the warp being dyed to one color and the filling to another.

Furthermore, there is, commercially speaking, an increase of luster on goods treated 35 according to my process which seems to coincide with the theory that while single color light reflects at only one angle, multi-color light, such as is produced on my fabric through the application of a second color 40 on an individual thread, will make such thread reflect its gloss in an additional direction than if it were singly colored.

It is also to be understood that another 45 novel aspect of this invention is that the above process tends largely to make the ribbed character of the goods disappear (see Fig. 3 of the drawing) and thereby make the finished product or fabric suitable for purposes for which the same goods when converted 50 in the ordinary piece-dyed way would not be suitable.

In passing the fabric 2 through the machine between rollers 3 and 4, there happens by reason of its shallow engraving 55 slight coloring or "specking" (Fig. 4) on one surface only and not changing at all of the original color of the cloth on one face thereof; it is desirable only to treat in the

way herein specified one side of the cloth, 60 which produces as found from practical experience, an effect of a variable color since the warp and fillings are lost to an ordinary observer; the specks of coloring matter, which held in the greatest quantities on the outer surfaces of the warp threads 65 also are found in some degree on the filling, the entire "specked" or lightly colored surface giving the appearance of one changeable color, even though on microscopic examination it may be found that the original 70 color of the fabric shows forth between the surface-applied coloring matter in accordance with my invention.

In conclusion, it is to be understood, by reason of my observations and experiments, 75 that I have found that the minute application of color carried on an even surface will produce very even effects (distinct designs on smooth goods), which means that on smooth goods, not ribbed goods, the applying 80 of a coating of coloring matter will practically cause a blotching or smearing effect, but that by following out my improve process or method, a uniform treated surface is produced on uneven or rough 85 surfaced goods that gives a variable color effect to one side of the fabric; such rough or ribbed goods when treated in accordance with my process produces what appears to be a woven fabric, which is only possible because 90 of the ribbed warp and filling threads falling in the manner hereinafter described, as to create an impression on an ordinary observer that the surface-printed goods or fabric has been produced, not through 95 printing, but by a special weaving of a mixture of different colored warp and filling (woof) threads.

What I claim is:

1. The process of producing a new fabric 100 of manufacture, comprising the treating of only one surface of colored silk-warp ribbed piece goods to a minute application of evenly-distributed color.

2. The process of producing a new fabric, 105 showing essentially the effect of a material woven with a mixture of different colored warp and filling threads, by subjecting a silk warp ribbed material to a specking of its individual threads with minute quantities 110 of color entirely and evenly over only one of its surfaces.

In testimony whereof I hereunto affix my signature.

WILLIAM HENRY SCOTT, JR.
